BRACELET CLASP

Emil Rodriguez, New York, N. Y., assignor to
 Jacoby-Bender, Inc., New York, N. Y., a corporation of New York

Application December 24, 1942, Serial No. 470,012

1 Claim. (Cl. 24—241)

This invention relates to clasps for watch bracelets and more particularly to an improved center catch clasp for releasably securing the center of a watch bracelet.

The main desiderata of a center catch clasp are (a) security in its clasping function, and (b) ease and simplicity of manipulation or operation. With these should be joined structural simplicity, strength and attractiveness. The present invention pertains to a center catch clasp which collectively and uniquely embodies these desiderata.

The ideal watch bracelet center catch clasp must possess assurance or security in its clasping function. Therefore, the locking members thereof must be so constructed that the parts cannot be unlocked or loosened by accidental or other undesired engagement with an article of clothing or other object, such accidental loosening being one of the causes of lost bracelets and watches. In the clasp of the present invention, this object of security of the clasping function is effectively accomplished by the provision of locking members which are so protectively housed and arranged that the possibility of the unlocking part or parts thereof becoming accidentally engaged or operated is effectively minimized or entirely obviated.

Ease and simplicity of manipulation of such a clasp entail the accessibility of the parts and the facility offered for moving the same to both open and locked conditions. In the clasp of the present invention, the structure is so designed that the unlocking part or parts is rendered accessible for desired manual manipulation even though these parts are protectively housed and thereby made normally inaccessible to accidental or undesired engagement. These parts are also so constructed and designed that a stainless finger or finger nail manipulation or operation will serve to unlock these parts and move the same to bracelet open condition.

In addition to fulfilling these prime desiderata, the center catch clasp of my present invention is structurally sturdy, made up of few and simple parts, capable of ease of assembly or disassembly and offers an ornamentally attractive clasp design.

To the accomplishment of the foregoing and such other objects as may hereinafter appear, the invention relates to the improved center catch clasp and the structural organization thereof hereinafter sought to be defined in the claim and described in this specification in connection with the appended drawing, in which:

Fig. 1 is a view of the bracelet clasp of my invention showing the manner of its use;

Fig. 2 is a side elevational view thereof with parts broken away to reveal the internal construction thereof;

Fig. 3 is a view thereof taken in the plane of the line 3—3 of Fig. 2;

Fig. 4 is a view thereof taken in cross-section in the plane of the line 4—4 of Fig. 2;

Fig. 5 is a view thereof similar to Fig. 2 and showing the manner of unlocking the same;

Fig. 6 is a perspective view thereof showing the manner of dissociating or detaching the parts thereof for the purpose of opening the bracelet;

Fig. 7 is a perspective view of one of the locking members thereof; and

Fig. 8 is a perspective view of the mating member thereof.

Referring now more in detail to the drawing thereof, the watch bracelet center catch clasp of my present invention comprises essentially a pair of end links generally designated as A and B, the end link A being apertured and the end link B being formed as a housing and carrying the clasp members of the catch. The said clasp members in their generic aspects comprise a closure element generally designated as 10 for the housing link B, pivoted at the end of said housing link B and provided at its inner or free end with a latch engaging part which is receivable by the housing of the link B and which is adapted to mate or cooperate with a movable latch element generally designated as 11 arranged within said housing link B, the closure element 10 and the latch element 11 being arranged to interlock when the closure element is moved to its closed position as shown in Figs. 1 and 2 of the drawing. It is of the essence of the invention that these described parts are so constructed and arranged as to accomplish the main as well as the ancillary desiderata or objects of the invention above described.

The apertured link A comprises a member made of suitable sheet metal and formed to provide a body 12 fashioned at one end as a receptacle for receiving the bracelet cord ends 13, and fashioned at its opposite end to provide an aperture 14 for detachably receiving the closure element 10 of the clasp. This end link A is otherwise conventionally formed as is most clearly shown in Figs. 2, 5 and 6 of the drawing.

The other end link B is also made from suitable sheet metal and is formed at one end to provide a receptacle portion 15 for receiving the cord ends 16 of a watch cord bracelet 17, the same being formed at the other end generally designated as 18 for mounting and housing the members of the clasp. This end link B is as stated formed as a housing and provides for the main body 19 thereof a top wall 19, opposite side walls 20 and 21, and a bottom wall 19', the top wall being apertured as at 22 and the side walls 20 and 21 being formed at their outermost ends with the pintle bearing members 23 and 24. As part of this end link B may be considered the pintle

25, the pivot pin 26 and the rivet 27, all of which aid in anchoring the parts of the body in its formed condition.

The closure element 10 consists of a relatively elongated member pivoted at its outer end to the corresponding end of the link B and provided at its inner end with one of the locking elements of the clasp. This closure element 10 forms when in its closed position a top closure for the housing link B, covering and concealing from view the mounted and operating parts of the clasp. This closure element separately shown in Fig. 7 of the drawing comprises a member also made of suitable sheet metal and formed to provide a top closure part 28, a pivot pintle surrounding part 29 at one end thereof, and a downwardly hooked latch engaging part 30 at the other end thereof. The part 29 is made large enough to house the coil part 31 of a spring having the two ends 32 and 33, the end 32 engaging the body 28 of this closure element. The closure element with the said spring is pivotally mounted on the pivot pintle 25. The downwardly hooked part 30 is receivable by the aperture 22 in the end link B and the same is orificed at 34 and otherwise shaped to form a latch engaging part.

The latch element 11 separately shown in Fig. 8 and also suitably formed from sheet metal comprises an angle shaped element formed to provide a latch 35, a part 36 at right angles thereto against which the spring end 33 is adapted to bear, and a bearing 37 for receiving the pivot pin 26. The latch 35 is adapted to mate with the latch engaging part of the closure 10, being urged into this engagement by the action of the spring. This latch element pivotally mounted on the pivot pin 26 is housed within the housing link B.

By means of the construction thus far described, it will be seen that normally (with the bracelet applied and the clasp in locked condition) the closure element 10 is held locked by the mating or interengagement of the latch element 11 with the latch engaging part of the closure element 10. It will be further seen that these locking parts are concealed within and housed by the housing link B. From an inspection of Fig. 2 of the drawing, it will be further seen that the latch element 11 (and all of its parts) is below the level of the highest part of the closure element 10. It will be also noted that both the closure element 10 and the latch element 11 are pivotally mounted about horizontal axes and that the unlocking of the parts, held in their positions by the action of the spring ends 32 and 33, can be effected only by movement of the latch element 11 about its pivot and against the action of the spring. Due to this described construction and arrangement of the locking members, the parts cannot be unlocked or loosened by any accidental or other undesired engagement with an article of clothing or other object, the locking members being so protectively housed that the possibility of the unlocking part or parts thereof becoming accidentally engaged or operated is effectively minimized or entirely obviated.

To render the unlocking part or parts of the clasp accessible for desired manipulation even though these parts are protectively housed and thereby made normally inaccessible, the latch member 11 is made to protrude slightly from the

link housing B and to this end the latch thereof is preferably provided with a finger or finger nail engaging portion 38 which protrudes from the housing and which is adapted to be engaged by the finger nail of the user as is most clearly depicted in Fig. 5 of the drawing. This protruding part 38 is also below the general level of the closure element 28, and if desired this closure element may be formed (from the metal struck out to obtain the orifice 34) with a protruding portion 39 which forms a guard for the latch protruding portion 38 (to guard the latter from any accidental engagement). This arrangement is best depicted in Fig. 2 of the drawing. From this construction it will be seen that the latch member is rendered accessible for the desired manual manipulation. It will also be observed that the described parts are so constructed and designed that the latch member 11 may be operated by a strainless finger or finger nail manipulation, it only being required to move the latch member from a position shown in Fig. 2 to that shown in Fig. 5 of the drawing to cause a closure member to be released and to be permitted to spring to its open position shown in Fig. 5 of the drawing. It will also be observed that the substantial length of the closure member 28 and also the fact that it is formed with a hook shaped end provides additional assurance against bracelet or watch loss, since after the parts have been sprung to open position, the bracelet has to be manually detached by moving the apertured end link A off or out of the closure element of the other end link B.

The manner of making and using the center catch clasp of the present invention and the many advantages thereof will, in the main, be fully apparent from the detailed description thereof. It will be further apparent that some changes may be made in the construction and arrangement of parts without departing from the spirit of the invention defined in the following claim.

I claim:

45 A center catch clasp for watch bracelets comprising a pair of end links, one of said end links being apertured, the other of said end links being formed as a housing and carrying the clasp members, said clasp members comprising a closure element for the top of the housing link pivoted about a horizontal axis at the end of the said link and provided at its inner free end with a downwardly hooked latch engaging part receivable by said housing link, a latch element pivoted within said housing link also about a horizontal axis and mating with said latch engaging part of the closure element to lock the latter when the same is moved to closed position, a finger engaging portion on said latch element protruding from the top of said housing link and engageable to move the latch element to release the closure element for movement to open position, and a spring anchored to the closure pivot and having one of its ends acting on the closure element to urge the same to open position and the other of its ends acting on the latch element to urge the same to locking position, the said closure element when in open position being adapted to be moved into or out of the aperture of said first mentioned link.
